CLAIM

The ornamental design for a bulletproof insert for backpacks as shown and described.

DESCRIPTION

FIG. 1 is a front view of a bulletproof insert for backpacks showing my new design;

FIG. 2 is a right side view thereof, the left side being a mirror image of the right side;

FIG. 3 is a top view thereof, the bottom being a mirror image of the top; and,

FIG. 4 is a left front perspective view thereof.

1 Claim, 4 Drawing Sheets
